F. P. KNOWLTON.
FEATHER DRESSER.

Patented July 2, 1836.

Francis Knowlton of the town of Claremont in the county of Sullivan and State of New Hampshire,
Letters of Patent

The schedule referred to in these Letters Patent, and making part of the same, containing a description in the words of the said Francis F. Knowlton himself of his Improvement in the Steam Feather Dresser.

Be it known, that I Francis F. Knowlton of the town of Claremont, in the county of Sullivan and State of New Hampshire, have invented a new and useful improvement in the machine for dressing feathers, called Knowlton's Improved Steam Feather Dresser, which is described as follows, reference being had to the annexed drawings of the same, making part of this Specification—

This machine consists of a frame A about 7 feet long 4 feet wide and 6 feet high, composed of four posts, side and end pieces and two all around with thin boards forming a light case for the feathers except a space on the top for their introduction which is covered with cloth B and two round apertures in the ends for the ends of the hollow shaft hereafter described to turn in—

One side of the case opens on hinges for taking out the feathers. The other side D likewise opens on hinges for removing the case hereafter described. The case or box is made in two parts so that the upper part E can be removed to obtain access to the interior. The top of the case is made in an oblique the shape of an obtuse angle, one half of which is covered with a cloth as before mentioned. Near the center of the case is constructed a semi circular metal receiver F to hold the feathers pierced with apertures for the escape of dirt &c. through G, the pan below one side O of which connects with an hinge and opens for the discharge of the feathers. Through the center of the case extends a hollow shaft H whose

ends turn on the apertures before mentioned in the ends of the case. Around this shaft is formed a hollow cylinder $\mathfrak{L}$ into which the steam is introduced for heating the feathers and over this cylinder is mounted a nail $\mathfrak{K}$ or similar for agitating the feathers which nail is fastened to the cylinder and turns with it by means of a cog-wheel $\mathfrak{L}$ fastened on the end of the hollow shaft into which is ground a pin $\mathfrak{M}$ turned by a wheel $\mathfrak{N}$. The steam is introduced from a boiler $\mathfrak{O}$ into the hollow shaft by a pipe $\mathfrak{P}$ furnished with a valve $\mathfrak{Q}$ to regulate it, and from the hollow shaft it passes into the hollow cylinder through an aperture $\mathfrak{R}$ in the shaft, and back again into the shaft through another aperture $\mathfrak{S}$ and from thence it passes out of the machine through a pipe $\mathfrak{T}$ at the other end of the case furnished also with a valve $\mathfrak{U}$ to regulate it.

There is a neck $\mathfrak{V}$ near one end of the cylinder for drawing off the condensed steam at part $\mathfrak{W}$ before mentioned or if it be necessary the dirt extracted from the feathers is placed below the nozzle.

The steam being introduced into the cylinder through the hollow shaft, the feathers are fast onto the case (in the nozzle) powdered with a solution of chloride of lime and water. The nozzle is then turned which turns the hollow shaft cylinder and nail $\mathfrak{K}$. The nail is used to agitate the feathers and keep them in continual motion - after remaining in the machine till quite dry which will be known by the cloth on the top becoming dry, the side of the case is to be opened and the door of the nozzle turned down which will discharge the feathers completely cleaned and having the appearance of new feathers.

The hollow shaft and cylinder may be furnished with a heat or formed for heating the feathers by placing a parallel lining around one half of the nozzle at such distance from it as to have a space between them large enough for steam sufficient to heat the interior of the case to the degree required, the steam being admitted at one end and discharged at

at the other

Opp'n of claim as my invention and which I desire to
secure by Letters Patent consists in the combination and arrangement
of the several parts of the Machine as before described for
dropping feathers, particularly in the manner of introducing &
discharging them, and also in the manner of heating the feathers
by means of steam introduced between the side of the concave
and the lining surrounding it, in the manner here described.—
I consider no claim to the use of a hollow shaft, cylinder or reel.

Wherefore

Opp'n of
Sam'l Stollmire

Francis P. Knowlton
